UNITED STATES PATENT OFFICE.

PAUL LEON PRICE, OF MOUNT VERNON, NEW YORK.

DESIGN FOR A FLOOR GRATING.

Application filed March 2, 1927. Serial No. 20,936. Term of patent 14 years.

To all whom it may concern:

Be it known that I, PAUL LEON PRICE, a citizen of the United States of America, residing at Mount Vernon, in the county of Westchester and State of New York, have invented a new, original, and ornamental Design for a Floor Grating, of which the following is a specification, reference being had to the accompanying drawing, forming part thereof.

Figure 1 is a plan view of a grating, showing my new design, and Figure 2 is an edge view of the same.

I claim:

The ornamental design for a floor grating, as shown.

PAUL LEON PRICE.
